FIRE EXTINGUISHER CABINET

John Blendl, Warren, Mich., assignor to Metal Cabinet Company, Warren, Mich.

Filed May 6, 1971, Ser. No. 141,095

Term of patent 14 years

Int. Cl. D29—01

U.S. Cl. D16—2

Fig. 1

Fig. 2

FIG. 1 is a front perspective view of a fire extinguisher cabinet showing my new design; and

FIG. 2 is a top plan view thereof.

The undisclosed rear portion of the cabinet is plane.

I claim:

The ornamental design for a fire extinguisher cabinet, as shown and described.
